The ornamental design for a tote lid, as shown and described.

DESCRIPTION

FIG. 1 is a front perspective view of a tote lid;

FIG. 2 is a top plan view thereof;

FIG. 3 is a bottom plan view thereof;

FIG. 4 is a front elevational view thereof; and,

FIG. 5 is a left side elevational view thereof.

The ornamental design which is claimed is shown in solid lines in the drawings.

The broken lines in the figures depict environmental subject matter only and form no part of the claimed design.
